ABSTRACT: An electromagnetic pickup for rapid connection to or disconnection from a stringed instrument of the zither type having a chord bar bridge supported at the sides of the strings has an elongated electromagnetic bar for positioning beneath the strings, the bar having tabs for frictional retention by the ends of the chord bar bridge and a control connected to one of the tabs with leads to the electromagnetic bar.

DETACHABLE ELECTROMAGNETIC PICKUP AND CIRCUIT FOR STRINGED MUSICAL INSTRUMENT

BACKGROUND OF THE INVENTION

The invention is in the field of musical instruments having sound amplifiers. In the past these have been mounted in various ways and have been permanent fixtures which are not easily mounted or removed. Since many instruments are purchased or are in use which lack electronic sound amplifiers, there has been a need for a pickup which can be easily mounted on an instrument and also easily removed.

SUMMARY OF THE INVENTION

Briefly stated, the present invention includes an elongated bar electronic pickup of low height so that it may be received on top of the housing of an instrument and beneath its strings. The bar has short extensions from each end which are frictionally received and retained beneath the ends of the chord bar housing of an instrument such as a zither, and a control means connected to one of the extensions having leads connected to the pickup.

In the drawing:

FIG. 1 is a plan view of a lower end portion of a zither with an embodiment of the present invention mounted thereon;

FIG. 2, a side elevation;

FIGS. 3, 4 and 5, enlarged sections on the lines 3-3, 4-4 and 5-5 respectively of FIG. 1;

FIG. 6, a perspective to an enlarged scale of an embodiment of the invention; and

FIG. 7, a schematic circuit diagram.

With further reference to the drawings, there is illustrated the lower portion of a zither body 10 having a multiplicity of strings 11 which are mounted in spaced relation above the top 10' of the body. The zither includes chord bar structure comprising chord bar retainers or housings 12 and 13 in which a plurality of chord bars 14 are removably mounted. The chord bar retainers are mounted on the top of the instrument secured by fasteners 15, one at each end of each retainer. By removal of two screws for one of the retainers 13 and loosening of the screws holding the retainer 12, a thin sheet member may be positioned for retention by the chord bar retainers.

The device of the present invention includes an elongated bar 20 having a central electromagnetic portion 21 retained between side flanges 22 and has end flanges or extensions 24, 25.

5 The electromagnetic portion 21 is of a nature which is highly sensitive to magnetic excitation such as a multiplicity of coils of fine wire in a ferromagnetic base, such structure being well known to those skilled in the art. The mounting of such structure adjacent to vibrating strings causes electrical impulses to be transmitted to the leads thereto and these in turn may be amplified by conventional electronic apparatus. In order to transmit the impulses received from the member 21, at least one lead extends from the member 21 to the control elements 26, 27. A standard connection 28 for a lead to an amplifier and speaker is provided at one side of the control member.

In the use of the device, the fastening members 15 holding the retainer 13 are removed or loosened sufficiently to permit the bar to be slipped therebeneath and the fastening members 15 holding the retainer 12 are loosened sufficiently to receive 20 the flange 24 at the other end of the bar. The fasteners 15 are then tightened and the instrument is ready to be connected to the amplifier.

I claim:

1. An electronic pickup for an instrument of the type having 25 a plurality of strings, a bridge structure overlying the strings and mounted on each side thereof, said bridge structure being removable, said pickup comprising a relatively long, relatively flat electromagnetic bar, a tab of reduced thickness extending from each end of the bar and adapted to be mounted beneath 30 the bridge, one tab under each side of the bridge, control means adjacent one of the tabs, and means electrically connecting the control means to the electromagnetic means in said bar.

2. The invention of claim 1 in which said control means is 35 directly connected to said one tab whereby said tab supports the control means.

3. An electronic pickup for a stringed instrument comprising 40 a relatively long, relatively flat electromagnetic bar, means extending from said bar for connection to an instrument, and control means magnetically and electrically connected to said bar, said control means adapted to be electrically connected to amplifier means.
